US00D369591S

United States Patent

[19]

Kondo[11] **Patent Number:** **Des. 369,591**[45] **Date of Patent:** ****May 7, 1996**[54] **ELECTRONIC COMPUTER**

685063 8/1986 Japan .

[75] Inventor: **Osamu Kondo**, Tokyo, Japan

(List continued on next page.)

[73] Assignee: **Kabushiki Kaisha Toshiba**, Kawasaki,
Japan[**] Term: **14 Years**[21] Appl. No.: **41,920**[22] Filed: **Jul. 12, 1995****Related U.S. Application Data**

[63] Continuation of Ser. No. 26,824, Aug. 4, 1994, abandoned.

[30] **Foreign Application Priority Data**

Mar. 29, 1994 [JP] Japan 6-8236

Primary Examiner—Freda Nunn*Attorney, Agent, or Firm*—Banner & Allegretti, Ltd.[57] **CLAIM**

The ornamental design for an electronic computer, as shown and described.

DESCRIPTION

FIG. 1 is a top, front and right side perspective view of an electronic computer showing my new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a bottom plan view thereof;

FIG. 7 is a rear elevational view thereof;

FIG. 8 is a front elevational view thereof in the closed position;

FIG. 9 is a right side elevational view thereof in the closed position; and,

FIG. 10 is a top plan view thereof in the closed position.
